UNITED STATES PATENT OFFICE

CAMILLE HENRI FUCHS, OF NEW ROCHELLE, NEW YORK

INTERNAL COMBUSTION ENGINE

Application filed June 25, 1929. Serial No. 373,618.

This invention relates to improvements in internal combustion engines or motors, and consists of an improved arrangement and operating relation of the cylinders, pistons and associated crank shaft, designed to give materially improved power production and particularly to eliminate the conditions causing back pressures or knocking of the motor at low speeds, and in addition stalling of the 10 motor resulting therefrom. My improved motor accordingly is peculiarly adapted for improved operation under the low speed conditions of modern traffic.

The improved features of the present invention are moreover readily incorporated in motors of the standard 6 and 8 cylinder type as at present largely used, in addition to motors of other and greater cylinder number.

An important feature of the present invention consists in modifying the head of the motor so as to provide a motor wherein the cylinder bores are united in pairs by a combustion chamber whereby the two pistons are operable in a single combustion chamber in conjunction with an improved piston and crank throw relation best designed for producing maximum compression at the interval of ignition to obtain a movement of the gases to improve the mixture of the explosive charge and to compound the pressure generated in a manner to produce an effective propelling force with the elimination of the back pressure conditions at relatively low speeds common to the conventional motor design.

The foregoing and other improved features and advantages of my present improvements will be more fully understood by reference to the accompanying drawings wherein like reference characters are applied to the corresponding parts in the several views.

Referring to the drawings:

Figure 1, is a vertical cross sectional view of a motor embodying the features of the present invention, the section being taken at the left centrally through one cylinder bore and at the right through the next adjoining and associated cylinder bore;

Figure 2, is a central vertical longitudinal section through a portion of the motor show-

ing the associated and mutually operated piston arrangement; and

Figure 3, is a vertical longitudinal sectional view taken on the line 3—3 of Figure 1 illustrating the valve arrangement.

In the approved design of motor construction embodying the features of the present invention, as here shown, 1 indicates an integrally cast multiple cylinder block having the usual series of vertical parallel and longitudinally aligned cylinder bores 2, within which are fitted the usual pistons 3 connected by the piston rods to the cranks 5 of the crank shaft 6 journaled in the usual bearings in the crank case 8.

The upper ends of the cylinder bores are closed by the usual integrally formed head block 10, secured to the upper surface of the motor block one, and formed with the usual water jacket chamber 11 and at its under side with the combustion chambers 12. The head block is further formed with the threaded openings 14 to the combustion chambers to receive the spark plugs 15 for ignition of the fuel charge. The cylinder block 1, following the conventional arrangement is formed with the water jacket chamber 16 of the cooling system and with the intake and exhaust ports 17 and 18 associated with each cylinder bore. It is also provided with the usual valve seats 19 opened and closed by the usual valves 20 and 21, operated by cams 22, 23 on cam shaft 24; the cams engaging the usual tappets 26 in alignment with valve stems 27 which are provided with the collars 28 engaged by the usual valve return springs 29 in accordance with standard construction.

In accordance with the present invention, the motor is arranged to operate upon the four-stroke cycle principle, with the cylinder bores operatively united in pairs whereby two pistons (preferably adjoining) are operable in a single combustion chamber, and in the same cycle of operation. For this purpose the combustion chambers 12 associated with adjacent cylinder bores are connected by an opening or passage 30 to form a single combustion chamber mutual to or communicating with a pair of the cylinder bores and the pistons operating therein.

In further accordance with the invention, the crank throw or relative angularity of the cranks associated with the mutually operated pistons of the united combustion chamber, are arranged at slightly different angles whereby one crank is advanced with relation to its associated crank at an angle of approximately 30 degrees, with the result that when one piston is at the extreme of its upward stroke, the associated piston of the mutual combustion chamber, will be slightly advanced on the downward stroke with relation thereto, and with the connecting rod and crank out of toggle and in effective power transmitting position. With the timing of the ignition to occur at this time, the ignition of the fuel charge will take place at the interval of greatest compression with the compounded force generated within the united combustion chamber effective upon the advanced piston (at the right as shown) throughout the interval that the associated piston is in dead center or toggle relation to its crank.

As a result of this improved arrangement the maximum pressures generated by the expansion of the gases will be fully effective for propulsion, initially acting upon the advance piston, and thereafter upon both of the mutually associated pistons of the united chamber. The ignition is preferably timed to occur at the interval of greatest compression, and is accordingly fully effective at both high and low speeds to transmit the generated power, and as aforesaid eliminating back pressures such as would tend to stall the motor.

While the drawings illustrate the invention with respect to a related pair of cylinder bores and pistons, it will be understood that the other of the cylinder bores and pistons of any multi-cylinder motor are similarly united to operate in pairs by a similar provision of mutually communicating combustion chambers and with a similar angular relation of the mutually acting cranks. As is customary, the timing of the ignition and valve operating cams is such that each of the associated pairs of pistons will be operating at a different stage of the cycle with relation to another associated pair of pistons.

With relation to each of the combustion chambers in the construction, as shown, double ignition is provided although, as will be readily understood, a single spark plug for each explosion chamber may be employed, if desired.

The improved structure as herein illustrated, is desirable as a simple modification of the standard construction of overhead valve motor to embody the improved principle of operation of my invention in that it allows of converting the standard structure by simply employing a modified head with the re-

quired changing of the timing of the valves and ignition, and the employment of a properly formed crank shaft designed to permit the pistons to be operated in pairs and in a corresponding stroke of the cycle.

I have accordingly provided an improved design and structural arrangement adapted in operation to compound the explosive force with a relative arrangement of the pistons whereby such force will be fully effective in its propelling action with the further advantage of effecting the ignition at the interval of maximum compression without reducing obstructive back pressures under conditions of both high speed and low speed operation. In addition thereto, there is a very desirable and advantageous movement of the compressed fuel which agitation or turbulence communicates the ignition more rapidly. Moreover, the improved arrangement prolongs the time interval of maximum compression whereby the ignition may more readily be effected to obtain the maximum propelling effect, and further by the improved crank arrangement having an annular difference of not more than 30 degrees allows for the explosion of the gas while the pistons are substantially at the initial point of their power stroke thereby avoiding objectionable overheating.

While my improved features are here shown applied to an automobile engine or motor of the overhead valve type, it will be readily understood that the same principles of construction are likewise applicable to sleeve valve type engines or rotary valve motors, and that the structure may be otherwise modified without departing from the invention, as defined in the appended claims. It is accordingly intended that all matter herein shall be interpreted as illustrative, and not in a limiting sense.

Having described my invention, I claim:

1. A multi-cylinder bore internal combustion engine adapted for operating on the four stroke cycle principle comprising a cylinder block having a plurality of equi-diameter cylinder bores, a head block portion formed at its under side with a combustion chamber mutual to and uniting a pair of cylinder bores, pistons operatively fitted within the bores, a crank shaft suitably journaled, connecting rods from the pistons to the crank shaft, said crank shaft having its cranks of equal throw and operatively related to the mutually acting pistons in angular relation of not more than substantially thirty degrees, means operative to control the intake and exhaust of the mutually connected cylinder bores and combustion chamber and means for igniting the explosive charge within the combustion chamber at the interval of highest compression and with the retarded crank at substantially its uppermost position whereby its associated crank will be angularly ad-

vanced substantially to a position out of toggle relation, and said chamber being formed to have substantially the same, operating combustion area related to each of the piston 5 tons.

2. An internal combustion engine of the four stroke cycle type comprising a cylinder block having a plurality of equi-diameter cylinder bores, a head block portion formed 10 at its under side with combustion chambers each of which is mutual to and unites a pair of cylinder bores and formed with horizontal upper chamber walls overlying substantially the full cross-sectional area of the bores, a 15 crank shaft suitably journalled, connecting rods from the pistons to the crank shaft, said crank shaft having its cranks of equal throw and operatively related to each combustion chamber in angular relation of not more than 20 substantially thirty degrees, said cylinder

block being formed with intake and exhaust ports communicating with the combustion chambers, valves operative to open and close the intake and exhaust ports, means for operating the valves for four stroke cycle operation and means for igniting the explosive charge within the combustion chambers at the interval of highest compression and with the retarded cranks at substantially their uppermost position whereby the associated cranks will be angularly advanced substantially to a 70 position out of toggle relation and said horizontal chamber walls being spaced to have substantially the same spaced relation to the upper surfaces of the pistons at the combustion 75 interval.

Signed at New Rochelle in the county of Westchester and State of New York this 4th day of June, A. D. 1929.

CAMILLE HENRI FUCHS.
